UNITED STATES PATENT OFFICE.

ALBERT G. SEWELL, OF WEST SCARBORO, MAINE, ASSIGNOR TO GARLAND MANUFACTURING COMPANY, A CORPORATION OF MAINE.

SOFT-FACE HAMMER.

Application filed July 25, 1927. Serial No. 208,224.

This invention relates more particularly to improvements in the manufacture of hammers, provided with a relatively soft striking face, so that they may be used upon 5 and about machinery without injuring the surfaces struck thereby. Hammers of this character have been made with faces of various materials such as lead, rubber and rawhide, but, ordinarily, rawhide is preferred. In any case, particularly when rawhide or the like is used, I have found it desirable to provide for readily replacing a worn face.

The primary object, therefore, of the 15 present improvement is to provide a hammer with striking faces of rawhide or other suitable relatively soft material, which may be readily renewed when worn out or battered down to such an extent as to require replacement.

In the present instance, the rawhide face members are preferably formed by rolling a strip of rawhide to the desired diameter and inserting it as a plug in a socket or recess 25 in the end of the hammer head. Continued use of this type of hammer ultimately wears down the rawhide or soft material striking face, and the plug of rawhide or the like becomes so battered that a new striking face 30 is required. With ordinary types of rawhide hammers, there is no convenient arrangement or means for renewing battered down or worn striking faces, and when a hammer becomes so badly worn as to require replacement, a complete new hammer 35 must be procured.

In the present instance, a further object is to provide a suitable wedging member, mounted in the socket or recess of the hammer head, and arranged so as to be readily forced out or removed therefrom, when it is desired to renew the rawhide striking face of the hammer. My improved wedging member preferably comprises a disc of sheet 45 metal provided with a plurality of prongs or wedges adapted to enter the relatively soft material of the rawhide or the like face member, so as to wedge the material of the latter into close frictional engagement with the 50 walls of the socket or recess, to thereby retain the soft face member in place. In this connection, it will be understood that in using my type of hammer, continual hammering with the face thereof will

seat the face member more firmly on the 55 wedging prongs. Obviously, this is desirable, particularly when rawhide is used, for the latter is subject to shrinkage and the continued hammering enables the wedging action to take up any shrinkage 60 and continue to retain the plug-like face member in the socket or recess of the hammer head.

By mounting the wedging member loosely in the bottom of the socket or recess in the 65 hammer head, as in the present instance, and providing a hole or suitable opening in the head, communicating with the bottom of the recess, through which a rod or other device may be inserted, the renewal of a worn 70 out striking face member is facilitated. Thus, by hammering or otherwise thrusting a rod or suitable device against the wedging member, the latter, with the striking face member, can be forced or driven out of the 75 socket or recess, after which a new striking face member may be forced into the socket, to be secured therein by the wedging member, as previously described.

In order to illustrate my improvement, one 80 form thereof is shown in the accompanying drawings, in which Fig. 1 is a perspective view of the complete hammer; Fig. 2 is a transverse section thereof, with a dotted indication of the removal of one striking face; 85 Fig. 3 is an end or face view of the hammer, and Fig. 4 is a perspective of the wedging member.

Referring to the drawings, it will be seen 90 that the head A of the hammer, which may be formed of cast iron or other suitable material, is provided with the usual handle B. In the present instance, the hammer head A is substantially cylindrical and is preferably provided at each end with a cylindrical 95 socket or recess C, formed by annular flanges D, integral with or otherwise secured to the head A, as seen more particularly in Figs. 2 and 3 of the drawings. In the present instance, I mount in the recess or sockets C, striking face members E, of relatively soft material, which in the present instance, are preferably coils of rawhide, each formed from spirally rolling rawhide strips F, as 100 more particularly shown in Fig. 3. In rolling the rawhide strips F, for forming the rawhide striking face members E, care should be exercised to see that the face mem-

bers or rawhide plugs, when finished are of a diameter permitting them to be readily inserted in the sockets or recesses C without much play.

In order to firmly secure the rawhide striking face members E in the sockets C, a wedging member G is preferably mounted in the bottom of the socket or recess, as will be seen in Fig. 2. The wedging member G is preferably formed as a disc or plate of sheet metal, of suitable size, shape and thickness, having a plurality of upwardly or outwardly projecting wedges or prongs H, adapted to penetrate the relatively soft material of the face member E, and force the latter into firm frictional engagement with the inner wall of the recess C. It will be understood that this wedging member may be made in any suitable or preferred manner and is preferably mounted in the socket or recesses C, so that the prongs or wedges H will be in position to properly engage the rear ends of the plug-like face members.

An important feature, however, of the present improvement is that the wedging members G are removably placed or loosely mounted in the sockets and held in place by the striking face members which they wedge in the sockets. The head A of the hammer is preferably provided with notches or openings K, formed in any suitable manner and communicating with the recesses C, through the bottoms thereof, so that a rod L, tool, or other suitable device may be brought into contact with the wedging member G, whereby the latter, together with the striking face, may be driven or forced out of the socket or recess. This arrangement is more particularly indicated in Fig. 2 of the drawings, which shows, in dotted lines, the rod L, passing through one of the openings at K to force out the wedging members G and the associated face member E, as represented by the dotted line positions thereof. In the present form of my improvement the sides of the head of the hammer are cut away at M, down to the bottoms of the sockets or recesses C, so as to produce the openings K. The dotted lines in Fig. 3, represent the walls M of the transverse cuts on the hammer head and outline the openings K for access, from the rear, of the tool or rod L, to forcibly remove the face members as just described.

From the above description, it will be

readily understood that when my improved hammers are assembled, the rawhide or other soft material faces E may be forced, by a suitable press or otherwise, into the sockets or recesses C of the hammer head, the material of the face members being thereby forced onto the wedges or prongs H of the wedging members G, as indicated in Fig. 2 of the drawings. In this manner, the rawhide striking faces are firmly seated and secured in the ends of the hammer head A, and the hammers are preferably marketed complete, in this finished form. When the face members R become battered or worn to such an extent that replacement thereof becomes desirable, my improvement permits the ready removal thereof, by simply forcing or driving out the worn face members, and replacing it with a new face member. As previously pointed out, the face members E may be readily removed by means of a rod L, engaging the rear of the wedging member G, through the opening K, thereby permitting the face members to be hammered or forced out of the sockets C, so that new face members may be inserted.

It will be understood that while I have shown one form of my improvement, in which the soft material face members are removable with and by forcing the wedging member out of the socket or recess, in which the face member is secured, it will be understood that I do not wish to be limited to the specific arrangement or construction shown and described, for various modifications therein may be made without departing from the spirit and scope of the invention.

I claim:

In a hammer, the combination of a head provided with recesses for the insertion of soft face members, said recesses being provided with openings at the bottoms thereof, wedging prongs extending outwardly from plates loosely placed in the bottoms of said recesses, said plates extending over said openings, and relatively soft face members adapted to be secured in said recesses by the spreading action of said wedging prongs, the arrangement being such that by driving a punch, inserted through said openings, against said plates, the plates and said soft face members may be forced out of the respective recesses to permit replacement of the face members.

ALBERT G. SEWELL.
